Attorney, Agent, or Firm—Calfee, Halter & Griswold LLP[57] **CLAIM**

The ornamental design for a classroom building, as shown.

DESCRIPTION

FIG. 1 is a top, front, and left side perspective view of a classroom building;

FIG. 2 is a rear elevational view thereof;

FIG. 3 is a front elevational view thereof;

FIG. 4 is a right side elevational view thereof;

FIG. 5 is a left side elevational view thereof; and,

FIG. 6 is a top view thereof.

A view of the bottom of the classroom building has been omitted due to its plain and unornamental appearance.
